SAFETY DEVICE FOR ELECTRICAL APPARATUS

Application filed November 25, 1929. Serial No. 409,458.

This invention relates to a safety or protective device for electrical apparatus.

I have seen fit to illustrate my invention as embodied in X-ray mechanism to protect the X-ray tube from excessive temperatures, but I wish it to be understood that I contemplate its use with other types of electrical apparatus which are subject to high temperature either because of excessive current flow, 10 mechanical friction, such as is present in an ordinary bearing, or heat radiation from a heating coil, arc or filament.

It is an object of this invention to produce a safety device which is susceptible of actuation due to direct transmission of heat from the part to be protected, as distinguished from electrical safety devices depending upon excessive current flow to cause a high temperature within the safety device.

20 It is also an object of this invention to produce a device which will notify the operator of the mechanism by a suitable visual signal that the apparatus has become excessively heated.

25 And it is still further an object to produce these desirable results with a mechanism of simple, reliable and economical construction, which may be produced in large quantities at a relatively small price so that it may find 30 a ready market.

Further features and objects of the invention will be more fully understood from the following detail description of the accompanying drawings, in which

35 Fig. 1 illustrates a simple, electrical circuit for an X-ray tube and shows the relative position of the safety device and X-ray tube, and

40 Fig. 2 is a sectional side elevation of the safety device.

Looking at Fig. 1, wires 1 and 2 represent the low voltage primary circuit which may be varied from zero to a maximum value of about 220 volts, depending upon the size and 45 type of X-ray apparatus utilized and the class of work desired to accomplish. T represents a high tension transformer, wherein 3 illustrates the primary windings connected to the low voltage wires 1 and 2, and 4 represents the secondary or high tension wind-

ings adapted to be connected to the X-ray tube. One side of the secondary or high tension circuit is connected by means of wire 6 to the cathode terminal 7 of the tube X, this cathode terminal 7 is usually made in the 55 form of a screw so that the tube may be conveniently secured into an electric socket. The terminal 7 is connected to the cathode C within the evacuated glass bulb of the tube X. The other side of the secondary or high 60 tension windings 4 is connected by means of wire 9 to the terminal 10 of the safety device.

A common type of commercial X-ray tube is equipped with radiating fins R, usually in 65 the form of thin discs attached to the extension of the anode A which extends outwardly from the evacuated glass portion of the tube. These radiator fins or discs, as the name would imply, are for the purpose of 70 dissipating the heat generated at the anode. The anode arm is usually made of copper and is generally a continuous piece extending through the radiator discs inwardly through the evacuated glass tube to a point opposite 75 and adjacent to the cathode. The beveled end of the anode is equipped with a tungsten target 12. With this construction the heat generated at the anode is transmitted through the copper body of the anode, 80 which is usually in the form of a stem of substantial diameter, to the radiator discs R which are cooled by the surrounding air. Radiator discs R are mounted upon a suitable sleeve adapted to slip over the outer end of 85 the stem of the anode and to be secured in place by a knurled screw, axially disposed in the end of the stem. I have seen fit to design my safety device so that it may be easily 90 and readily substituted for the screw with which a common type of commercial tube is equipped.

It is obvious that in tubes not provided with the construction described above other suitable mounting may be provided to furnish a heat conducting path between the anode and the safety device.

This construction will be further described in the detailed description of Fig. 2.

It is sufficient for the purpose of the de- 100

scription of the circuit to say that an electrical circuit exists through the safety device S from the terminal 10 to the left hand end of the anode as viewed in Fig. 1 so that 5 a complete high tension circuit from the high tension windings through the tube is obtained.

Fig. 2 illustrates in detail the construction of the safety device itself. It comprises a 10 glass tube 15 with removable metal spring clip heads 16 and 17 which may be pulled off of the glass tube for the purpose of replacing the fusible element of the safety device, as will be explained more fully hereafter.

15 Head 16 is equipped with a terminal device shown in the form of a double ring shaped substantially in the form of a figure 8 and adapted to pass through aperture 18 in head 16 and illustrated with the circular portion 19 on the outside of the head 16 and a circular or hooked portion 20 on the inside thereof.

Head 17 is secured to a knurled nut 21 by means of a screw 22 which is adapted to pass 25 through the head 17 and nut 21 and extended for a substantial distance beyond, say about $\frac{1}{2}$ " so that screw 22 may be screwed into the threaded hole furnished in the outer end of the anode stem in place of the screw which 30 is used to hold the radiator discs in place, and thus the safety device may be readily secured to the end of the anode stem adjacent to the radiator discs and will serve to hold the radiator discs in place instead of the 35 usual screw furnished for that purpose. The knurled nut will serve to enable an operator to screw the safety device into place. The head of screw 22 is furnished with the usual slot and in said slot is soldered by means of 40 a metal 25 of low melting point a link herein illustrated in the form of a washer 26. The metal 25 should possess a sufficiently low melting point so that heat transmitted through the anode A and screw 22 will melt 45 the metal 25 before the anode A reaches a dangerously high temperature.

The spring 30 joins the hook 20 of terminal 10 to the washer or link 26 and is so 50 calibrated as to normally exert a tension on the link 26 when the spring is in the position shown in Fig. 2.

When X-ray tubes are subjected to an excessive current or are continuously utilized 55 for a long period of time, the anode A is apt to become so hot as to permanently impair the function of the X-ray tube and even cause the tungsten target 12 to drop out of the beveled end thereof and thus cause breakage of the tube which is a very undesirable 60 thing because X-ray tubes are very expensive.

With my safety device the heat generated 65 at the anode will be transmitted through the stem of the anode to the outer end thereof and through the metallic screw 22 to the fusi-

ble metal 25 which will melt and release the link 26 which will be drawn toward the terminal 10 or to the left, as viewed in Fig. 2, and when this device is installed on an X-ray apparatus where a high voltage and low amperage is used, the length of the device may be such that an arc will be drawn from the head of the screw 22 to the link 26 after it has been released and pulled by the spring toward the left, and this arc will be 70 plainly visible through the glass body 15 and will serve as a signal to the operator of the machine that the X-ray tube has become overheated.

It is my intention to supply my safety device with replaceable portions consisting of screw 22, and link 26 inset in fusible metal 25, so that the operator may refill the safety device in its original condition by merely removing it from the tube, disengaging the 85 head 17 and the members attached thereto and replacing screw 22 and link 26 soldered therein which may be hooked to the spring 30 by pulling the spring 30 outwardly by means of a hooked wire or buttonhook, for instance. 90 In this manner the safety device may be readily and quickly reassembled at a minimum cost and expense.

The length of time required to replace the screw and link is desirable rather than undesirable, as it forces the operator to allow the tube to stand long enough to cool off. 95

If my safety device is installed with some other type of electrical apparatus wherein a lower voltage and perhaps a higher amperage is utilized, it may not be desirable to design the glass body portion 15 so that an arc will be drawn and maintained between the terminals of the device, but instead it may be desirable merely to break the electrical circuit so as to disconnect the current from the apparatus. This result of course, may be obtained by the same construction illustrated in the figures and described above. 100

Whereas, I have described my invention by reference to specific forms thereof, it will be understood that many changes and modifications may be made without departing from the spirit of the invention. 110

I claim:—

In a safety device for an X-ray tube, a body having a transparent portion, a fusible link in said body connected into and made part of the electric circuit for carrying the current for the tube, a metallic screw attached to said fusible link and adapted to pass through and project from said safety device so that a considerable portion thereof may be screwed into the anode stem of an X-ray tube, a head on said screw having a slot in which the fusible metal of said link may be disposed to produce a close and intimate contact between said metal and screw to facilitate the transmission of heat from the latter to the former, a spring in said body connected to said 125

link and normally maintained under tension and adapted, upon melting of the link, to break the electric circuit and draw an arc across the intermediate space between the 5 broken ends within the transparent body to serve as a signal to the operator of the X-ray machine.

In testimony whereof I have signed this specification this 16th day of November, 1929.

10 CARL B. BRAESTRUP.
